UNITED STATES PATENT OFFICE.

THOMAS R. OWEN, OF LOS ANGELES, CALIFORNIA, ASSIGNOR TO HORACE L. CUTTER, OF LOS ANGELES, CALIFORNIA.

HYGIENIC APPLIANCE FOR SOUND-TRANSMITTERS.

SPECIFICATION forming part of Letters Patent No. 768,768, dated August 30, 1904.

Application filed January 24, 1902. Serial No. 91,119. (No model.)

To all whom it may concern:

Be it known that I, THOMAS ROBINSON OWEN, a citizen of the United States, residing at Los Angeles, in the county of Los Angeles and 5 State of California, have invented new and useful Improvements in Hygienic Appliances for Sound-Transmitters, of which the following is a specification.

This invention relates to improvements upon 10 hygienic appliances for sound-transmitter mouthpieces, for which Letters Patent of the United States, No. 654,096, were granted to me July 17, 1900.

Some of the objects of the present invention 15 are to provide superior and simpler means for holding the hygienic strip taut across the mouth of the sound-transmitter, to increase the facility of applying said strip to the strip-holder ready for use, to avoid any liability of 20 tearing or fraying the edges of the strip, and to reduce to a minimum the contact between the holder and that face of the strip which is presented to the user.

A further object is cheapness, simplicity, 25 and increased ease of manufacture.

In the present appliance the holder for the axle upon which the roll of the hygienic strip is carried comprises two resilient standards having holes, respectively, in which the ends 30 of the axle are journaled. Said standards are preferably bowed toward each other, so that the portion around the axle-bearing will frictionally contact with and press against the ends of the roll, thereby to act as a brake to 35 hold the same against racing. Provision is also made whereby the action of the brake upon the roll is uniform at all times.

Another feature of the invention consists 40 in the construction of a member of the strip-holder, which is bent to form three walls of the tension-guide for the strip as well as a seat for the member which forms the other wall of the strip-guide and cutter, across the edge of which the strip is to be drawn to tear off the 45 used portion thereof from time to time, as required.

The accompanying drawings illustrate this invention.

Figure I is a perspective view of the im-

proved appliance in place on a telephone-transmitter mouthpiece ready for use. Fig. II is a rear view of the appliance detached from the mouthpiece. The sanitary strip is shown in position ready for use as it appears after a used portion has been torn off. Fig. III is 55 a side elevation of the appliance detached. Fig. IV is a vertical mid-section on line IV IV, Fig. II. Fig. V is a fragmental section on line V V, Figs. III and IV. Fig. VI is an exaggerated plan section on line VI VI, Figs. 60 III and IV. Fig. VII is a view of the guiding and tearing plate detached. Fig. VIII is an enlarged section of one of the standards. Fig. IX is a plan of the member *b* of the 65 strip-holder.

1 designates means constructed to hold and guide a portion of the hygienic strip 2 across the open end of the mouth of the sound-transmitter *a*. The same may consist in a body formed of a plain strip of sheet metal bent in 70 four members *a b c d* and adapted to fasten upon the telephone or other sound-transmitter and constructed to extend on opposite sides of the mouthpiece thereof substantially as in the said patented device. The arm *d* of the 75 strip-holder 1 is constructed to form three walls of a tension-guide *y* for the hygienic strip. With this object in view the end of the body is bent downward to form the tension-guide member *d* in the usual manner, and said 80 member *d* is bent at its edges to form shoulders *e*, and outside said shoulders is bent upon itself to form plate-retainers *f* to hold the member 3, which forms the front wall of the tension-guide. The depth of the shoulders *e* 85 is approximately equal to the thickness of the hygienic strip 2, and the member 3 is a fraction longer than the space between the bends *g* of the ears and is outwardly bowed at the middle, as indicated at *h*, so that when the 90 end of the hygienic strip 2 is pointed, as shown in Fig. I, it can be readily passed through the guideway formed between the plate 3 and the arm *d*. The plate 3 presses the sides of the strip against the member *d* and holds the 95 same friction-tight, while the greater portion of the strip is free from contact with said plate 3.

In order to provide a most simple and efficient means for holding the rolled portion *i* of the hygienic strip, a strip *4*, of sheet-steel or other suitable resilient material, is bent to fit against the arm *b* and to extend from said arm in two inwardly-bowed standards *j*, which are provided with holes *k* to form bearings for the axle *5* of the roll *i* of the hygienic strip. The holes in said standards may extend in bent slots *6* in the inwardly-bowed portion *7* of the standards. Said slots preferably slant downward rearwardly and then extend forward and terminate in undercut journal-bearings *k*. The purpose of this undercut is to prevent the strain of the strip *2* on the roll *i* from displacing the axle *5* when the strip is drawn downward to bring a new surface in front of the receiver. Each of the standards *j* is preferably formed with an inwardly-projecting boss *8* at the bearing-holes *k*. The bosses *8* are held by the resilient standards *j* against the roll, near the axis thereof, so that the frictional pressure upon the roll remains constant until the roll is fully unwound.

The plate *3* of the tension-guide *y* is preferably furnished at its edges with shoulders *m* to fit against the projections *f* of the arm *d* to prevent the plate *3* from being forced upward by the strip *2* in the act of tearing.

n designates a rivet, fastening the resilient strip *4* to the arm *b* of the body of the holder. Preferably the strip will be wound in a roll upon a perforated core *o*, of wood, through which the axle *5* may readily be passed preparatory to applying the strip to the holder. The bosses *8* may press against the wooden core *o* of the roll.

In practice the hygienic strips will be put up in rolls ready for application to the holder and the free end *p* of the strip will be pointed to facilitate threading through the open space *q* at the middle of the plate *3*. The roll will be inserted between the standards *j* and the axle *5* brought into the bearing *k*. Then the point *p* of the strip will be inserted through the space *q* and the strip drawn down, so that its edges are clasped between the plate *3* and the member *d*. When the user desires to bring a new surface into position, he will draw the strip and tear it off in the usual way. The plate *3* is wider than the member *d*, so that the lower end of the strip is left free behind the plate *3* to be drawn down by the fingers of the user in order to again bring a new surface into play.

The parts of the strip-holder may be stamped and pressed from three strips of sheet metal or other suitable material, and each of said strips is of a practically plain and simple form, as will readily be understood from the drawings.

The cost of assembling the parts is comparatively small owing to simple construction.

9 designates gains desirably formed in the

edges of the member *b* of the body to hold the standards *j*.

s designates hole for the rivet *n*.

What I claim, and desire to secure by Letters Patent of the United States, is—

1. A hygienic appliance for a sound-transmitter mouthpiece comprising in combination a flexible strip; means constructed to hold and guide a portion of the strip across the open end of a mouthpiece; an axle carrying a portion of the strip in the form of a roll; and a support for said axle consisting solely of a resilient strip of metal constructed to frictionally contact with the ends of the roll near the axle.

2. A hygienic appliance for a sound-transmitter mouthpiece comprising in combination a flexible strip; means constructed to hold and guide a portion of said strip across the open end of a mouthpiece; an axle carrying a portion of the strip in a roll; and resilient means constructed to form bearings for the ends of the axle and having inwardly-projecting bosses adapted to press against the ends of the roll near the axle.

3. In a hygienic appliance for sound-transmitters, a strip-holder having arms and a resilient member fastened to one of said arms and bent therefrom at its end portions, said end portions being bowed toward each other and furnished with holes through the bows for an axle, and an axle supported by said bows.

4. In a hygienic appliance for sound-transmitters, a strip-holder having resilient standards respectively furnished with bent slots terminating at the lower ends in undercut bearings and provided at such portions with inwardly-projecting bosses adapted to frictionally engage with the ends of the roll.

5. In a hygienic appliance for sound-transmitters, the combination of a body constructed to hold and guide a strip; resilient standards extending from said body and furnished with holes to form bearings for an axle and with bosses projecting toward each other; a roll of flexible material; an axle in said roll and in said bearings, the standards being constructed to press the bosses against said roll.

6. The combination of a strip-holding member constructed to be connected with a sound-transmitter and furnished with arms, one of which is bent to form three walls of a stripway and a seat for a plate; means on the other arm for holding a flexible strip; a strip held by said means and extending in said stripway; and a plate seated in said seat and forming the other wall of said stripway.

In testimony whereof I have signed my name to this specification, in the presence of two subscribing witnesses, at Los Angeles, California, this 17th day of January, 1902.

THOS. R. OWEN.
